CLAIM

We claim the ornamental design for a brake dust filter, as shown and described.

DESCRIPTION

FIG. 1 shows a perspective view of the brake dust filter showing our new design;

FIG. 2 shows a right side elevational view thereof;

FIG. 3 shows a left side elevational view thereof;

FIG. 4 shows a rear elevational view thereof;

FIG. 5 shows a front elevational view thereof;

FIG. 6. shows a top plan view thereof;

FIG. 7 shows a bottom plan view thereof; and,

FIG. 8 shows a rear perspective view thereof.
